HANGER FOR PICTURE FRAME OR THE LIKE

Harry Mandel, New York, N. Y.

Application November 13, 1948, Serial No. 149,621

Term of patent 3½ years

(Cl. D29—20)

To all whom it may concern:

Be it known, that I, Harry Mandel, a citizen of the United States, and a resident of New York city in the Borough of the Bronx, in the county of the Bronx and State of New York, have invented a new, original, and ornamental Design for Hanger for Picture Frame or the like, of which the following is a specification, reference being had to the accompanying drawings, forming part thereof.

In the drawings:

Fig. 1 is a view in elevation of a hanger for picture frame or the like embodying my new design.

Fig. 2 is a side view thereof with the cords broken away at the upper ends thereof.

The broken lines are shown for illustrative purposes only.

I claim:

The ornamental design for a hanger for picture frame or the like, substantially as shown and described.

HARRY MANDEL.
